(57) **CLAIM**

The ornamental design for a masquerade-style air freshener device, as shown.

DESCRIPTION

FIG. 1 is a perspective view of masquerade-style air freshener device embodying the present invention;

FIG. 2 is a front view of the air freshener device;

FIG. 3 is a rear view of the air freshener device;

FIG. 4 is a left side view of the air freshener device;

FIG. 5 is a right side view of the air freshener device;

FIG. 6 is a bottom view of the air freshener device; and,

FIG. 7 is a top view of the air freshener device.

The broken line disclosure represents stitching.
